his Atty.

UNITED STATES PATENT OFFICE.

FREDERICK C. WASHBURN, OF NEW BEDFORD, MASSACHUSETTS.

PIN BOARD.

Application filed January 8, 1923. Serial No. 611,209.

To all whom it may concern:

Be it known that I, FREDERICK C. WASHBURN, a citizen of the United States of America, and resident of New Bedford, in the county of Bristol and State of Massachusetts, have invented new and useful Improvements in Pin Boards, of which the following is a specification.

My invention relates to the construction 10 of pin boards such, for instance as are employed in textile mills to hold bobbins or cops, and has for its object the construction of a pin board in which the pins are more securely held than heretofore, and which shall 15 be easy to repair when it becomes necessary to replace a bent or displaced pin with a new one.

Pin boards have heretofore, in the best mode of construction, been made of three-ply glued wooden boards, by first gluing 20 together two of the board plies with their grains crossing, boring holes in this two-ply board into which the pins are fitted, projecting from one side, the flanges attached 25 to the other ends of the pins resting against the other side of the two-ply board; then gluing the third ply to the first two, over the pin-flanges, pressing the board in a veneer press so as to squeeze the wood of the 30 board plies against the pin-flanges, clamping them in place and thus providing as secure an anchorage for the pins as was possible under the circumstances.

Obviously, whenever one of the bobbin pins in such a board requires replacement, the work of repair is difficult, and the results not wholly satisfactory.

By my improvements herein described, a pin board is produced in which the three plies of the base may be assembled at a single gluing and pressing, the pins secured in the base even more tightly and rigidly than heretofore, from which a damaged pin may be easily removed, and in which a new pin can be fixed as firmly and securely as the original pin.

In the drawings hereto annexed, which illustrate my improvements in several forms 50 all of which involve the same principle of construction,

Figure 1 shows a portion of a pin board base in vertical section, with the several members of my improved pin-cushioning devices separated;

Figure 2, is a view similar to Fig. 1, with the locking member in place around

the pin, and the bridging member ready to be forced into engagement with the locking member;

Figure 3, is a similar view, showing the 60 pin, locking member and wedging member in final position;

Figures 4 and 5 are similar views of an alternative construction;

Figures 6 and 7 are similar views of an 65 other alternative; and

Figures 8 and 9 are similar views of a modification slightly departing from the specific features of Figs. 1 to 3, inclusive.

Figures 1, 2 and 3 represent what I believe to be the best form in which to construct my improvement in pin boards. In these and in all other figures, B represents a portion of a pin board base, consisting of a three-ply glued board, C the side of a 75 pocket, preferably bored in the base in true cylindrical form, P a bobbin pin, and F the pin flange, to which the pin P is firmly secured, or with which it may be integral. The pin flange F is adapted to rest on the 80 bottom of the pocket in the base B, and will preferably be nearly as large in diameter as the side C of the pocket. To secure the pin P and anchor it firmly in the base B, I employ two members, which are represented in the several figures of drawings by specifically variant forms; viz; a locking member and a wedging member. These two members are so proportioned that their aggregate section (taken in a plane parallel 85 with the axis of the pin) is greater in area than a section of the pocket-space, surrounding the pin, taken in a similar plane; and are so shaped that when forced together in the pocket-space around the pin, the wedging member spreads into an exteriorly conical form, compressively displacing the material of the base surrounding the pocket, and thus converting the pocket into a flaring 90 or undercut recess in the base B.

Thus, in Figs. 1, 2 and 3, the pin P stands in the pocket made in the pin board, resting on its flange F, which is lodged on the bottom of the pocket; the locking member E, straight on the outside but conical on the inside, so that it is an annulus of 95 downwardly flaring section, enters the pocket, making a snug fit with the side C (Fig. 2). The wedging member D, in this case a cylindrical annulus, slides with a close 100 fit over the pin P, and is dimensioned so that it will fill the larger diameter of the 105

downwardly tapering space between the pin P and locking member E. Then by means of a suitable tool, the wedging member D is forced into the tapering space, spreading the locking member outwardly and causing it to displace the material of the base B which surrounds the side C of the pocket. When the wedging member D is thus forced home, it and the locking member E are pressed 10 tightly on the top of the pin-flange F, clamping it securely against the bottom of the pocket.

Preferably, the material of which the locking member and wedging member are 15 made is denser and less compressible than the material of which the base B is composed, so that substantially all of the displacement of material by compression takes place in the base, thus producing an under- 20 cut or conical shape as pronounced as possible in the pocket, as the latter is finally formed. The locking and wedging members will, by preference be made of hard wood, such as maple, or of compressed fibre; 25 for purposes of removal and repair they should be of material easily cut by a reaming tool.

Should the pin P become damaged, it can 30 be easily replaced by cutting out the locking member or wedging member, or both, by means of a tubular boring or reaming tool, when the damaged pin can be taken out. Then a new pin will be placed in position and anchored by means of new locking 35 and wedging members, which will collectively form an inwardly flaring filler, tightly engaged in the pocket.

The above described mode of setting a pin 40 in the pin board gives the pin a firmer anchorage than was possible by the previously practised mode, above briefly described, because the material surrounding the pin and bearing on its flange is denser and harder than that of which the base B is composed, 45 and because, locally, the latter material is condensed by the compressive action of the locking member. In pin boards made by the old method, the third ply of the base was liable to be imperfectly glued around the pin 50 flanges, whereas in a board made by my improved method, the plies are securely glued together over their entire meeting surfaces; the pin pockets being bored after the plies are glued and set.

55 In Figs. 4 and 5, the wedging member D' is an annular truncated cone, fitting over the pin P, and flaring downwardly into the pocket, while the locking member E' is exterior to the wedging member, and is a cylindrical annulus, which will just enter the space between the thin end of the wedging member E' and the side C of the pin pocket. The outer lower edge of the locking member E' is here shown as chamfered or rounded, at e' , so as to guard against cutting into

the material of the base B when the locking member is being forced into its final position, shown in Fig. 4.

In Figs. 6 and 7, the arrangement and relationship of parts is essentially the same as 70 is shown in Figs. 4 and 5, and differ therefrom specifically in that the wedging member D², instead of being originally separate from and attached to the pin P, by being slid over it, is integral in material with the pin itself. In this instance the wedging member is represented by the material of which the conical surface flares downwardly and away from the prolongation of the cylindrical surface of the pin P, as indicated 80 by the dotted lines P'. The locking member E² (rounded at e^2) cooperates with this wedging member D² in the same manner as does the locking member E' with the wedging member D' of Figs. 4 and 5.

85 It is thus apparent that the locking member or the wedging member may provide the flare required to produce the spreading of the locking member against the side of the pocket, and the compression of the material 90 of the base B, which accompanies the change of shape produced in the pocket. Figures 95 9 and 9 illustrate how the taper or flare may be provided in part by each of the wedging and locking members (D² E²); the two together, whatever the specific variation, providing when assembled, an inwardly flaring plug of material securely lodged in a similarly flaring pocket, and tightly pressed 100 upon the pin flange.

In all the figures, the locking member (E, 105 E' or E²) is shown as of such height that when in place in the pocket it projects above the surface of the base B. This annular projection provides a seat around the pin P, 110 on which a bobbin will rest, when placed over the pin. This seat protects the softer material of the base B from becoming worn and grooved, as is the case in bobbin pin boards as heretofore made.

115 What I claim and desire to secure by Letters Patent is:

1. In a pin board, the combination of a base provided with a pocket, a pin, a flange secured to one end thereof, and adapted to 115 lodgment at the bottom of the pocket, a wedging member and a locking member, cooperating to form an inwardly flaring filler in the pocket-space, confining the pin flange 120 against the bottom of the pocket and compressively displacing the material of the base surrounding the pocket.

125 2. In a pin board, the combination of a base provided with a pocket, a pin, a flange secured to the end thereof and adapted to lodgment at the bottom of the pocket, a wedging member adjacent to the pin, and a locking member surrounding the wedging member, the wedging and locking members 130 cooperating to form an inwardly flaring

filler in the pocket space, confining the pin flange against the bottom of the pocket and compressively displacing the material of the base surrounding the pocket.

3. In a pin board, the combination of a base provided with a pocket, a pin, a flange secured to one end thereof, and adapted to lodgment at the bottom of the pocket, a wedging member and a locking member, 10 operating to form an inwardly flaring filler in the pocket-space, confining the pin flange against the bottom of the pocket, and compressively displacing the material of the base surrounding the pocket, one of said members projecting above the surface of the base to form a seat surrounding the pin.

4. In a pin board, the combination of a base provided with a pocket, a pin, a flange secured to the end thereof and adapted to 20 lodgment at the bottom of the pocket, a wedging member adjacent to the pin, and a locking member surrounding the wedging member, the wedging and locking members cooperating to form an inwardly flaring 25 filler in the pocket space, confining the pin flange against the bottom of the pocket and compressively displacing the material of the base surrounding the pocket, the locking member projecting above the surface of the 30 base to form a seat surrounding the pin.

5. In a pin board, the combination of a base provided with a pocket, a pin, a flange secured to one end thereof, and adapted to lodgment at the bottom of the pocket, a 35 wedging member and a locking member, cooperating to form an inwardly flaring filler in the pocket-space, confining the pin flange against the bottom of the pocket and compressively displacing the material of the base

surrounding the pocket, the locking member 40 composed of material less compressible than that of which the base is composed.

6. In a pin board, the combination of a base provided with a pocket, a pin, a flange secured to one end thereof and adapted to 45 lodgment at the bottom of the pocket, a wedging member adjacent to the pin, and a locking member surrounding the wedging member, the wedging and locking members 50 cooperating to form an inwardly flaring filler in the pocket space, confining the pin flange against the bottom of the pocket and compressively displacing the material of the base surrounding the pocket, the locking 55 member composed of material less compressible than that of which the base is composed.

7. In a pin board, the combination of a base provided with a pocket, a pin, a flange secured to one end thereof and adapted to 60 lodgment at the bottom of the pocket, a wedging member adjacent to the pin, and a locking member surrounding the wedging member, the wedging and locking members 65 cooperating to form an inwardly flaring filler in the pocket space, confining the pin flange against the bottom of the pocket and compressively displacing the material of the base surrounding the pocket, the locking member composed of material less compressible than that of which the base is composed, and the locking member projecting 70 above the surface of the base to form a seat surrounding the pin.

Signed by me at New Bedford this 29th 75 day of December, 1922.

FREDERICK C. WASHBURN.
